UNITED STATES PATENT OFFICE.

GEORGE W. BAUGHMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed October 26, 1926, Serial No. 144,267. Renewed March 19, 1928.

My invention relates to railway signaling, and particularly to signaling of the type involving track circuits. One feature of my invention is the provision of means for producing a considerable number of indications without line wires.

I will describe one form of apparatus embodying my invention and will then point out the novel features thereof in claims.

10 In the accompanying drawings, Figs. 1 and 1^A, when placed end to end in the order named, constitute a diagrammatic view showing one form of apparatus embodying my invention. Figs. 2 to 8, inclusive, are curves 15 illustrating the operation of the track relays shown in Figs. 1 and 1^A.

Referring to Figs. 1 and 1^A, the reference characters 1 and 1^A designate the track rails of a railway along which traffic normally moves in the direction indicated by the arrow. These rails are divided by insulated joints 2 to form a plurality of track sections A—B, B—C, * * * G—H. Each track section is provided with a track circuit comprising a source of current located adjacent the exit end of the section and two track relays located adjacent the entrance end. The immediate source of current for each track circuit is a transformer designated by the reference character L with an exponent corresponding to the location, the primary of which is connected with a source of alternating current not shown in the drawing. The secondary 19 of each transformer 30 is connected across the track rails as hereinafter explained. The two track relays for each section are designated by the reference characters J and K with suitable exponents. Each relay J comprises two 35 windings 3 and 4, the latter of which is constantly supplied with alternating current of a fixed relative polarity from the secondary 19 of the adjacent transformer L. Each relay K is responsive to reversals of the polarity of uni-directional current, and as here shown, it comprises two windings 5 and 6, the latter of which is constantly supplied with direct current from a battery 18. It is understood, however, that the winding 6 may be replaced by a permanent magnet, if desired. The 45 two windings 3 and 5 of the two relays for each section are connected in series across the rails of the section.

It will be seen that each relay J is responsive to reversals of the relative polarity of alternating current in the rails of the associated section; I will assume that when the rails are supplied with alternating current of normal relative polarity, the contacts 7, 55 8, 9, 10 and 11 of this relay are swung to the left, and that when the rails are supplied with alternating current of reverse relative polarity these contacts are swung to the right. Each relay K is responsive to the polarity of uni-directional current in the track winding 5, and I will assume that when this current is of normal polarity contacts 12, 60 13 and 14 are swung to the left, whereas when this current is of reverse polarity these contacts are swung to the right. It will be observed that the relays K are not responsive 65 to full-wave alternating current in the track windings 5.

Located adjacent the entrance end of each section is a signal designated by the reference character S with an exponent corresponding to the location. Each signal is controlled by contacts 11 and 14 of the associated relays J and K. Each signal in the form here shown comprises seven electric lamps designated 0, 1, 2, 3, 4, 5 and 6. Lamp 70 0, when lighted, gives a stop indication; lamp 1, when lighted, gives the next most restrictive indication; lamp 2, when lighted, gives a less restrictive indication than lamp 1, and so on to lamp 6, which gives the least 75 restrictive indication of any of the lamps.

The supply of track circuit current from each transformer L to the associated track section is controlled in part by asymmetric units 15, 16, 17 and 21. These units may be 80 of any suitable type, such for example, as that shown in application for Letters Patent of the United States filed January 7, 1925, by Lars O. Grondahl, for uni-directional current-carrying devices, Serial No. 1,111.

As shown in the drawing, the section immediately to the left of point A is occupied by a train W, so that track circuit current is shunted from the track windings 3 and 5 of relays J^A and K^A, with the result that both 85 of these relays are de-energized. Alternating current flows from the left hand terminal of the secondary 19 of transformer L^A, through contact 8 of relay J^A, contact 13 of relay K^A, to the upper track rail 1 of section 90 105

A—B, and from the lower track rail 1^a of this section, through contact 12 of relay K^A and contact 7 of relay J^A to the right-hand terminal of secondary 19. The current thus supplied to the rails of section A—B is of what I will term "normal relative polarity", and it will be seen that it is full-wave alternating current. Relay J^B is energized in the normal direction and relay K^B is deenergized. The conditions in these relays are indicated in Fig. 3, from which will be seen that the voltage in winding 3 of relay J^B is in phase with the voltage in winding 4 of this relay (Fig. 2), whereas the alternating current in winding 5 of relay K^B will not co-operate with the direct current in winding 6 to produce torque in the relay. Lamp 1 of signal S^B is lighted, the circuit being from the left-hand terminal of secondary 19 of transformer L^B, through contacts 14 of relay K^B, lamp 1 and contact 11 of relay J^B to the right-hand terminal of secondary 19.

The track circuit for section B—C is from the left-hand terminal of the secondary 19 of transformer L^B, through contact 8 of relay J^B, contact 12 of relay K^B to rail 1^a, and from rail 1 through contact 13 of relay K^B and contact 7 of relay J^B to the right-hand terminal of secondary 19. This current is of reverse relative polarity and is full-wave alternating current, so that, as indicated in Fig. 4, relay J^C is energized in reverse direction and relay K^C is opened. Lamp 2 of signal S^C is lighted through a circuit which will be obvious from the drawing.

Referring now to section C—D, track circuit current flows from the left-hand terminal of secondary 19 of transformer L^C, through contact 8 of relay J^C and contact 13 of relay K^C to rail 1 and from rail 1^a, through contact 12 of relay K^C, asymmetric unit 15 and contact 7 of relay J^C to the right-hand terminal of secondary 19. This current is of normal polarity, but due to the asymmetric unit 15 each positive half-wave is blocked, and the conditions in relays J^D and K^D are indicated in Fig. 5. The half-wave alternating current of normal relative polarity in winding 3 of relay J^D co-operates with the alternating current in winding 4 to energize this relay in the normal direction and the uni-directional current of reverse polarity in winding 5 of relay K^D co-operates with the direct current in winding 6 to energize this relay in the reverse direction. Lamp 3 of signal S^D is therefore lighted, the circuit for this lamp being obvious from the drawing.

Referring now to section D—E, the track circuit is from the left-hand terminal of secondary 19 of transformer L^D, through contact 9 of relay J^D, asymmetric unit 16, contact 12 of relay K^D to the lower track rail 1^a, and from the upper rail 1, through contact 13 of relay K^D and contact 10 of re-

lay J^D to the secondary 19. This current is of reverse relative polarity and the positive half-wave is suppressed by the asymmetric unit 16, so that the conditions in the track windings of relays J^E and K^E are as indicated in Fig. 6. It will be noted that both relays J^E and K^E are energized in the reverse direction. Lamp 4 of signal S^E is therefore lighted by virtue of a circuit which will be obvious from the drawing. 75

Referring now to section E—F, track circuit current flows from the left-hand terminal of secondary 19 of transformer L^E, through contact 9 of relay J^E, contact 13 of relay K^E to track rail 1, and from track rail 1^a, through contact 12 of relay K^E, asymmetric unit 17 and contact 10 of relay J^E to secondary 19. This current is of normal relative polarity and the negative half-waves are suppressed by the asymmetric unit 17, so that, as indicated in Fig. 7, relay J^F is energized in the normal direction and relay K^F is also energized in the normal direction. Lamp 5 of signal S^F is therefore lighted by virtue of a circuit which will be obvious from the drawing. 80 85

The track circuit for section F—G is from the left-hand terminal of secondary 19 of transformer L^F, through contact 12 of relay K^F to the lower track rail 1^a, and from the track rail 1, through contact 13 of relay K^F and asymmetric unit 21 to the right-hand terminal of secondary 19. This current is of reverse relative polarity and the negative half-waves are suppressed by the asymmetric unit 21, so that, as indicated in Fig. 8, relay J^G is energized in the reverse direction and relay K^G is energized in the normal direction. Lamp 6 of signal S^G is lighted by a circuit which is obvious from the drawing. 90 95 100

In section G—H the track circuit current flows from the left-hand terminal of secondary 19 of transformer L^G, through contact 12 of relay K^G, to the lower rail 1^a, and from the upper rail 1, through contact 13 of relay K^G and asymmetric unit 21 to secondary 19. The conditions in section G—H are therefore the same as those in section F—G, so that track relay J^H is energized in the reverse direction, track relay K^H is energized in the normal direction, and lamp 6 of signal S^H is lighted. 110 115 120

It will be observed from the foregoing that in the form herein illustrated, each signal S gives seven distinctive indications, and that this is accomplished without any line wires other than those which would be required to supply alternating current to the transformers L. 125

Although I have herein shown and described only one form of apparatus embodying my invention, it is understood that various changes and modifications may be made therein within the scope of the ap- 130

pended claims without departing from the spirit and scope of my invention.

Having thus described my invention, what I claim is:

- 5 1. In combination, two electro-responsive devices, the first of which is responsive to uni-directional current but not to full wave alternating current, and the second of which has two windings and is selectively responsive to the relative phases of alternating currents or half-waves of alternating currents therein, means for constantly supplying one winding of said second relay with alternating current of fixed phase, means for supplying the said first relay and also the second winding of said second relay with full-wave alternating current of normal or reverse relative polarity or with only the positive or only the negative half-waves of alternating current of normal or reverse relative polarity, and signaling means controlled by said relays. 40
- 10 2. In combination, two electro-responsive devices, the first of which is responsive to uni-directional current and to reversals of the polarity of such current but is not responsive to full-wave alternating current and the second of which has two windings and is selectively responsive to the relative phases of alternating currents therein, means for constantly supplying one winding of said second device with alternating current of fixed phase, and means for supplying the said first device and also the second winding of said second device with full-wave alternating current of normal or reverse relative polarity or with only the positive or only the negative half-waves of alternating current of normal or reverse relative polarity. 45
- 15 3. In combination, two relays, the first of which is responsive to uni-directional current but not to full-wave alternating current or with only the positive or only the negative half-waves of alternating current of normal or reverse relative polarity, and signaling means controlled by said relays. 50
- 20 4. In combination, a stretch of railway track divided into sections, two relays for each section, the first of which is responsive to uni-directional current and to reversals of the polarity of such current, and the second of which has two windings and is selectively responsive to the relative phases of alternating currents or half-waves of alternating currents therein, means for constantly supplying one winding of said second relay with alternating current of fixed phase, said first relay and the second winding of said second relay being connected with the rails of the associated section, means controlled by the two relays for each section for supplying the rails of the section in the rear with full-wave alternating current of normal or reverse relative polarity and for at times blocking the positive half-waves or the negative half-waves of such current, and signaling means for said sections controlled by said relays. 55
